UNITED STATES PATENT OFFICE.

WILLIAM W. STEGALL, OF DICKENS, TEXAS.

DESIGN FOR A MEMBER FOR REPAIR-LINKS.

SPECIFICATION forming part of Design No. 32,192, dated February 6, 1900.

Application filed January 11, 1900. Serial No. 1,152. Term of patent 14 years.

To all whom it may concern:

Be it known that I, WILLIAM W. STEGALL, a citizen of the United States, residing at Dickens, in the county of Dickens and State of Texas, have invented and produced a new and original Design for a Member for Repair-Links; and I do hereby declare the following to be a full, clear, and exact description of the invention, such as will enable others skilled in the art to which it appertains to make and use the same.

This invention relates to a member for a link of the type comprising companion members combined in such a manner so that each constitutes a mousing for the other, the link being especially designed for repairing broken chains and connecting like parts to be united.

The characteristic features of the invention are longitudinally-aligned siamesed rings having entrance-openings at diagonally opposite points and adjacent to their connecting-piece, a pivot opening in the latter, an offstanding interlocking projection bordering upon the entrance-opening of one ring, and a corresponding indentation.

The design is fully illustrated in the drawings hereto attached and specifically set forth in the appended description.

In the drawings, Figure 1 is a perspective

view of a repair-link member, illustrating the 30 design. Fig. 2 is a top plan view.

Corresponding and like parts are referred to in the following description and indicated in both views of the drawings by the same reference characters.

The member comprises the siamesed rings 1 and 2, having entrance-openings 3 and 4 adjacent to the connecting-piece 5. These rings are longitudinally aligned and in the same plane, and the entrance-openings 3 and 4 are 40 at diagonally opposite points. A pivot-opening 6 is centrally disposed with reference to the connecting-piece 5. A depression or indentation 7 is formed in a side of a ring, and an interlocking offstanding projection 8 is 45 provided at one end of the entrance-opening and borders thereon.

Having thus described the invention, what is claimed as new is—

The design for a member of a repair-link, 50 substantially as herein shown and described.

In testimony whereof I affix my signature in presence of two witnesses.

WILLIAM W. STEGALL. [L. S.]
